DESIGN FOR A KNOB

Henry J. Kasch, Dayton, Ohio, assignor to The Kurz-Kasch Company, Dayton, Ohio, a corporation of Ohio

Application June 15, 1933, Serial No. 48,414

Term of patent 7 years

To all whom it may concern:

Be it known that I, HENRY J. KASCH, a citizen of the United States, residing at Dayton, Montgomery County, Ohio, have invented a new, original, and ornamental Design for a Knob, of which the following is a specification, reference being had to the accompanying drawing, forming a part hereof.

In the drawing, Fig. 1 is a plan view of a knob illustrating my new design. Fig. 2 is a side elevation thereof.

The dominant feature of the design for a knob, forming the subject matter hereof, is a fluted body of truncated conical form having on its top a convex boss surrounded by concentric beads between which are radially disposed flutes.

I claim:

The ornamental design for a knob substantially as shown and described.

In testimony whereof, I have hereunto set my hand this 5th day of May, 1933.

HENRY J. KASCH.
